DESHA TYPELEX TRUST ESTATE, OF FORT COLLINS, COLORADO.

KEY ACTION FOR TYPEWRITING AND OTHER KEY-OPERATING MACHINES.

Application filed March 24, 1927. Serial No. 178,087.

My invention relates to key-action for typewriters and other type bar and key operating machines, actuated means at all times operatively connecting the type bar and key lever, 5 moving the type bar to printing point upon the depression of a key lever and means reversely breaking the said connection after the printing impact of the type bar for the return of the type bar to normal position while the 10 key lever is in depressed position; this broad object being the subject matter of an application filed by me on November 5th, 1923, Serial No. 672,871, upon which issued Patent 1,643,203, September 20, 1927 as a contrain 15 distinction between previous devices comprising a detachable connection or gap at some point between the key lever and type bar after the latter has been given the movement necessary to effect the printing and before the 20 key lever has completed its movement.

A specific object of the present invention is to provide means of the character specified above which in the main is in the nature of another form of structure that may readily be 25 incorporated in certain typewriting machines requiring only slight modification of structural features of said machines as they now exist. I have shown my invention embodied, in the present instance, in a typewriter similar 30 to the L. C. Smith Brothers standard machine, and in which the invention may readily be incorporated by slight modification of structural features of the machine in effecting such incorporation. It should be understood, however, 35 that the invention is not restricted to use in a machine of this type, but may be employed wherever found available.

The desired principle of operation, new 40 mechanical functions, operative expedients, and other objects and advantages will, hereinafter be described in the following disclosure, and will be more particularly pointed out in the appending claims. In the accompanying drawings, wherein like reference 45 characters indicate corresponding parts in the various views.

In the drawings Figure I is a vertical section of a typewriting machine, one key-action only being shown in normal position; Fig. II 50 represents a view of the key mechanism similar to Fig. I, the key lever being shown in a depressed position and actuating the type bar. Fig. III, also is a key mechanism similar to Fig. I, the key lever being shown in a de- 55 pressed position and the type bar returned to

its initial position. Fig. IV is a skeleton view of the key mechanism for illustrative purposes in describing the mode of operation of machine shown. It is understood, of course, that for the sake of clearness and to avoid 60 complication of drawings the applicant has omitted to show or describe the remainder of key levers and type bars as well as other devices necessary or advisable in the complete 65 machine.

In the embodiment in Fig. I, 1 indicates the frame of the typewriter, 1^a indicates the front and 1^b the rear, having a common power driven paper carriage, the principal parts of the carriage not being shown in the drawing; 70 5 indicates the common platen carried by paper carriage; 6 indicates one of the usual type bars carrying type 7 at its front end, and having an eccentric pivot 9^a at the heel of rear end, and is arranged to turn on pivot 9 in the form of a 75 segment basket disposed vertically above the frame 10; and 10^a Fig. I indicating part of the basket frame subjecting the type bar 6 to "basket shift", thereby providing the type 7 with a common printing point A, as the type bar 6 turns on pivot 9 from the normal horizontal position of rest on the segment 11; 12 indicates one of the key levers carrying at the front end finger key 13, the rear end pivoted at 80 14 to bar 14^a in the rear of the machine, and is kept normally in its elevated position by return spring 15 supported by bar 15^a, at normal rest the key lever bearing against the under side of stop bar 15^b above the front part of the key lever 12, in the usual manner. 85

Key lever 12 is formed with an upward angular projection 16, and also provides a saddle-backed seat 17 for the reversely breaking actuating coupling hereinafter described.

The key lever 12 is described as having 95 two incidents of operation; namely, the incident of depression and incident of release. The incident of depression is disclosed by the downward movement of key lever 12 from radius B to radius C, and the incident of release is disclosed by the upward movement of key lever 12 back from radius C to radius B. The type bar 6 is described as having two incidents of operation, namely, the incident of response and the incident of recoil. The incident of response of type bar 6 is disclosed by the movement of the type bar from its initial rest radius E to printing point A, indicated by radius F, forming 100 arc G from pivot 9. The incident of recoil 105 are H from pivot 9. The incident of recoil 110

of type bar 6 is disclosed by its movement from its printing point A back to normal rest E. These incidents of operation are, of course, present in previous nonreversely breaking type bar actions in so far as the incident of response E to A of the type bar 6 occurs simultaneously with the incident of depression B to C of key lever 12, and the incident of recoil, A to E, of the type bar 10 occurs simultaneously with the incident of release C to B, of the key lever, but my invention relates to a later correlation of incidents of operation of the key levers with that of the type bar, in conforming to the reversely breaking action by which both the incident of response, E to A, of the type bar and incident of recoil, A to E, occur during the one incident of depression, B to C, of the key lever.

20 In this case, a novel form of reversely breaking actuating coupling peculiarly arranged between the key lever and a vibratory link accomplishes this operative expedient; the form of action and arrangement 25 of said reversely breaking actuating coupling being the subject matter of this application, hereinafter described.

18 indicates one of a series of vibratory levers disposed upwardly corresponding in 30 number with type bars 6 and key levers 12. Intermediately their ends, the vibratory links 18 are pivoted at 19 in a bar 20 extending across the machine, and each at its upper end is pivoted at 21 as usual to a backward pull 35 link 21^a which engages the type bar at pivot 9^a. 22 is a forward draw link curved downwardly extending forward of pivot 25, horizontally disposed at the side of the key lever actuated forwardly under expansive tension, 40 and operatively connected intermediately of its ends to the vibratory link. And 23 is a forward thrust link extending forward from pivot 26 normally operating under contractive tension actuating forward thrust, and 45 operatively connecting the draw link and key lever, said draw link 22 and thrust link 23 constituting the reversely breaking actuating coupling, which by way of connecting lever 18 and backward pull link 21 at all 50 times operatively connect the type bar and key lever. The draw link 22 is pivoted at 25 to the lower ends of the vibratory link 18, and the front end of the downward curved draw link 22 is pivoted at 24 to the front end of the 55 thrust link 23, the rear end of the thrust link 23 being pivoted at 26 to the upward angular projection 16 of the key lever 12.

The relative normal positions of pivots 24 and 25 are engaged in a line nearly horizontal with the key lever 12 as shown by broken line J J Fig. IV, disclosing the reversely breaking actuating coupling to be horizontally disposed as distinguished from being engaged perpendicular to the key lever. It 60 will be observed that draw link 22 is dis-

posed horizontally at the side of the key lever thereby utilizing the space between the key levers for compactness. Also it will be noted that the thrust link 23 operates in front of the upward projection of the key lever disclosing a forward thrust.

Instead of depending solely upon the agency of gravity for the recoil of the type bar, a return spring 27 may be employed. The front end of return spring 27 engages 75 the hole 27^a in the rear end of the trippet link 27^b which is pivoted at 27^c to the rearwardly projecting end 27^d of the draw link 22; the rear end of return spring 27 engages the hole 27^e in the cross bar 30, in the rear of the machine.

Upon depression of the key lever 12, the trippet link 27^b moves forward and upward and communicates at 18^a Fig. II with the rear edge of the vibratory link 18, hence the vibratory link 18 and the draw link 22 acts as a fulcrum to trip the front end of the thrust link 23 out of the saddled-backed seat 17 about the time the type 7 impacts the printing point A breaking reversely said coupling while the key lever 12 is in depressed position. The lower edge of the trippet link 27^b communicates at 12^a Fig. I with the upper edge of the key lever 12 returning said coupling to normal operative position upon release of the key lever.

23^a is an extended nose of the thrust link 23. The lateral angle 16^a of the upward angular projection 16 of key lever 12 provides that the under edge 23^b of the thrust link 23 may cooperate with the saddle-backed seat 17 on top of key lever 12, and the upper edge 23^a cooperates with the under side 20^a of the return bar 20 returning said coupling to normal operative position during the incident of release of the key lever.

The mechanical movements and operation thereof are important factors in providing the function of the key action. A further description of the operative principles therefore follows: The geometric circle H H Fig. IV, with a horizontal diametrical line J J, from the forward border pivot 24 to backward border pivot 25 circumscribes what is termed the actuating plane. The horizontal 115 diametrical line J J crossing the actuating plane, from the forward border pivot 24 to the backward border pivot 25 indicates the divert tension line dividing the actuating plane into an upper zone of response K and 120 a lower zone of reaction L; the upper zone of response K having to do with the response of the type bar 6 from radius E to radius F as the key lever 12 is being depressed from radius B to radius D; and the lower zone 125 of reaction L having to do with the recoil of the type bar 6 from the printing point A to radius E at rest as the key lever 12 is being continually depressed from radius D to radius C of depression. The normal or 130

idle position of the draw link 22 operates in the lower zone of reaction L as shown in Figures I, II, III, IV, and thrust link 23 operates within the forward radius of the 5 actuating plane.

- It is necessary that the forward draw link 22 and thrust link 23 be relatively major and minor in length, and link 23 be in such form and so engaged in hinge-fold fashion so as 10 to permit the interior pivot 26 to oscillate between the forward border pivot 24 and backward border pivot 25 in crossing and recrossing the horizontal divert tension line J J. In this case, the elements 22 and 23 of the 15 reverse breaking actuating coupling are unfolded during the incident of depression from radius B to radius D of the key lever 12 and simultaneously with the incident of response of the type bar 6 from radius E to 20 printing point A; and the elements 22 and 23 are folded during the remainder of depression, radius D to radius C of key lever 12 simultaneously with the recoil of the type bar 6 from printing point A back to radius E. 25 The saddle-backed seat 17 provided by the key lever 12 stops the forward border pivot 24 and effects responsive tension lock of thrust link 23 under influence of return spring 27 as the key lever 12 is being depressed from radius B to radius D. This 30 tension lock of thrust link 23 is also described as contractive tension lock meaning that while the key lever 12 is being depressed, the energy required to respond the type bar 6 35 effects contractive pressure or thrust from the interior pivot 26 to the forward border pivot 24 instead of expansive tension or pull. The contractive tension of thrust link 23 stops its oscillation and is moved bodily edge- 40 wise downward with the key lever 12, as shown in Fig. II, until the interior pivot 26 crosses the horizontal divert tension line J J into the zone of reaction L within the upward concavity of the draw link 22. Simultane- 45 ously with contractive tension lock of thrust link 23, draw link 22 operates under expansive tension between the forward border pivot 24 and the backward border pivot 25 while the key lever 12 is being depressed from 50 radius B to radius D to respond the type bar 6 from radius E to printing point A, and the expansive tension of link 22 being relaxed while the key lever continues the incident of depression from radius D to radius C 55 and simultaneously with the recoil of the type bar 6 from the printing point A back to radius of rest E.
- A change in relative positions of the forward border pivot 24 and the backward 60 border pivot 25 brings the interior pivot 26 down within the lower zone of reaction L within the upward concavity of the draw link 22 thereby releasing the contractive tension lock of thrust link 23.
- 65 The release of contractive tension-lock of

thrust link 23 permits it to resume oscillation upwardly reversely breaking the coupling about the time the type impacts the printing point A. When said coupling reversely breaks in the above manner there 70 being no further obstruction to the recoil of the type bar 6, it immediately recoils from A to E while the key lever 12 continues its incident of depression from D, to C and contacting with trip bar 34.

The dotted line M M indicates the correlative relationship of the border pivots 24 and 25 and the interior pivot 26 during the process of operation, viz: Dotted line M M Fig. I shows where the tri-pivotal relationship of pivots 24, 25 and 26 forms obtuse angle at the interior pivot 26 pointing upward within the upper zone of response during the normal position and effecting response of the type bar during the depression of the key 85 lever 12. Dotted line M M Fig. II shows about a 45° alignment of the border pivots 24 and 25 and the interior pivot 26 at the time the type bar completes its response or impact and begins to recoil. Dotted line M M Fig. 90 III shows an obtuse angle at the interior pivot 26 formed by the tri-pivotal relationship pointing downward within the zone of reaction L as the type bar 6 recoils.

Inherent to the nonreversely breaking key 95 action, whenever certain keys are accidentally and slightly depressed part way down they suspend their respective type bars along the type arc G interfering with the response and recoil of intentionally struck keys, but the 100 present invention provides the exigency that when the finger key 13 is slowly depressed, the type bar 6 responds to the degree on arc G corresponding to the radius of depression of the key lever 12 and from there automatically 105 recoils without impact with the platen. This is an inherent exigency of my invention referred to as the operative expedient by which type bars responding to slowly depressed keys part way down automatically 110 recoil without interfering with responding type, hence the name "automatic type bar recoil mechanism" or "automatic coupling". This operative expedient is accomplished by a trippet bar 34 in the following manner: 115 The downward movement of the draw link 22 is limited by communicating with trippet bar 34 engaged at the incident of depression of the key lever 12, Fig. II, thereby pushing the thrust link 23 out of the saddle-backed 120 seat 17 and when the key lever is slowly depressed the type bar having no momentum it drops back without printing impact.

Variations may be resorted to within the 125 scope of the invention, and portions of the improvement may be used without others.

What I claim as new and desire to secure by Letters Patent is:

1. In a typewriting machine, a type bar, a vibratory lever, means operatively connect- 130

ing the vibratory lever and type bar comprising a backward pull link, a key lever, actuating means at all times operatively connecting the key lever and vibratory lever to move 5 the type bar to the printing point upon the depression of the key lever comprising a forward draw link curved downwardly and horizontally disposed at the side of the key lever operatively connected intermediately of its 10 ends to the vibratory lever, and a forward thrust link operatively connecting the draw link and key lever, means actuating said connection to return the type bar after the printing impact while the key lever is in depressed position, means restoring said connection to normal operative position upon release of the key lever.

2. In a typewriting machine, a type bar, a vibratory lever, means operatively connecting 20 the vibratory lever and type bar comprising a backward pull link, a key lever, a reversely breaking actuating coupling comprising a forward draw link curved downwardly and horizontally disposed at the side of the key lever operatively connected intermediately of its ends to the vibratory lever, and a forward thrust link operatively connecting the draw link and key lever for moving the type bar to printing point upon 25 depression of the key lever, means reversely breaking said coupling after the printing impact to return the type bar to normal position while the key lever is in depressed position, means restoring said coupling to normal operative position upon release of the key lever.

3. In a typewriting machine, a type bar, a vibratory lever, pivoted intermediately of its ends, means operatively connecting said 40 vibratory lever and type bar comprising a backward pull link engaged horizontally, a key lever, a reversely breaking actuating coupling comprising a forward draw link curved downwardly and horizontally disposed at the 45 side of the key lever operatively connected intermediately of its ends to the vibratory lever, and a forward thrust link operatively connecting the draw link and key lever for moving the type bar to printing point upon depression of the key lever, means reversely breaking said coupling after printing impact of the type bar for returning the type bar to normal position while the key lever is in depressed position, means restoring said 50 coupling to normal operative position upon release of the key lever.

4. In a typewriting machine key action, a type bar, a vibratory lever, means connecting the vibratory lever and type bar comprising a backward pull link, a key lever, a reversely breaking actuating coupling comprising a forward draw link curved downwardly and horizontally disposed at the side of the key lever operatively connected intermediately of its ends to the vibratory lever,

and a forward thrust link operatively connecting the draw link and key lever, a normal operative position of the elements of said coupling being unfolded moving the type bar to printing point upon depression of the key lever, means folding said elements reversely breaking said coupling after the printing impact of the type bar, means restoring the folded elements of said coupling to normally unfolded position upon the release of the key lever.

5. In a typewriting machine key, a type bar, a vibratory lever, means operatively connecting the vibratory lever and type bar comprising a backward pull link, a key lever, a reversely breaking actuating coupling operatively connecting the vibratory lever and key lever comprising a forward draw link curved downwardly and horizontally disposed at the side of the key lever operatively connected intermediately of its ends to the vibratory lever, and a forward thrust link operatively connecting the draw link and key lever, said draw link and thrust link being relatively long and short in length moving the type bar to printing point upon depression of the key lever, means reversely breaking said coupling after printing impact of the type bar for returning the type bar to normal position while key lever is in depressed position, means restoring said coupling to normal operative position upon release of the key lever.

6. In a typewriting machine, a type bar, a vibratory lever pivoted intermediately of its ends disposed vertically and its upper end thereof vibrating backwardly, means operatively connecting the vibratory lever and type bar comprising a backward pull link, a key lever, a reversely breaking actuating coupling comprising a forward draw link curved downwardly and horizontally disposed at the side of the key lever and actuating forwardly operatively connected intermediately of its ends to the vibratory lever and a forward thrust link operatively connecting the vibratory lever and key lever moving the type bar to the printing point upon depression of the key lever, means reversely breaking said coupling after printing impact of the type bar for returning the type bar to normal position while key lever is in depressed position, means restoring said coupling to normal operative position upon release of the key lever.

7. In a typewriting machine, a type bar, a vibratory lever, means operatively connecting the vibratory lever and type bar comprising a backward pull link, a key lever, a reversely breaking actuating coupling operatively connecting the key lever and vibratory lever comprising a forward draw link curved downwardly, horizontally disposed at the side of the key lever, actuated forwardly under expansive tension and operatively con-

- 5 nected intermediately of its ends to the vibratory lever, a thrust link normally operating under contractive tension producing forward thrust operatively connecting the draw link and key lever for moving the type bar to the printing point upon depression of the key lever, means reversely breaking said coupling after printing impact of the type bar, means returning the type bar to normal position 10 while key lever is in depressed position, means restoring said coupling to normal operative position upon release of the key lever.
- 15 8. In a type key action, a type bar, a vibratory lever pivoted intermediately of its ends, means operatively connecting the vibratory lever and type bar comprising a backward pull link, a key lever, an upward angular projection intermediately the ends of 20 the key lever, a reversely breaking actuating coupling operatively connecting the key lever and vibratory lever comprising a forward draw link curved downwardly horizontally disposed at the side of the key lever actuating 25 forwardly and pivoted to the lower end of said vibratory lever, and a forward thrust link pivoted to said upward angular projection of the key lever moving the type bar to printing point upon depression of the key lever, means actuating the interior pivot downward across a divert tension line between the forward border pivot and a backward border pivot reversely breaking said coupling after printing impact of the type 30 bar for returning the type bar to normal position while the key lever is in depressed position, means restoring said coupling to operative position upon release of the key lever.
- 35 9. In a key action for key-operating machines, a type bar, a vibratory lever, means operatively connecting the vibratory lever and type bar comprising a backward pull link, a key lever, an upward angular projection intermediately the ends of the key lever, a saddle-backed seat forwardly of said upward projection on the key lever, a reversely 40 breaking actuating coupling operatively connecting the key lever and vibratory lever comprising a forward draw link curved downwardly horizontally disposed at the side of the key lever actuating forwardly, and 45 a thrust link operatively connected to the upward angular projection of the key lever riding said saddle-backed seat bodily downward moving the type bar to printing point upon depression of key lever, means limiting 50 the downward movement of the forward end of said thrust link tripping the latter off the saddle-backed seat reversely breaking said coupling after the printing impact of the type bar for returning the latter to normal 55 position while key lever is in depressed position, means for restoring the thrust link to the saddle-backed seat upon release of the key lever.
- 60 65 10. In a type key mechanism, a type bar, a vibratory lever means operatively connect- 110 ing the vibratory lever and type bar comprising a backward pull link, a key lever with an upward angular projection intermediately of its ends, a reversely breaking actuating coupling operatively connecting the key lever and vibratory lever comprising a forward draw link curved downwardly horizontally disposed at the side of the key lever, and a forward thrust link, a forward border pivot connecting the forward end of the draw link 115 and forward end of the thrust link above the key lever, a backward border pivot connecting the draw link and the lower end of said vibratory lever above the key lever, an interior pivot above a line drawn through the border pivots for connecting the rear end of the thrust link and upward angular projection of the key lever moving the type bar to printing point upon depression of the key lever, means actuating the interior pivot downward across a divert tension line between the forward border pivot and a backward border pivot reversely breaking said coupling after printing impact of the type 120 bar for returning the type bar to normal position while the key lever is in depressed position, means restoring said coupling to operative position upon release of the key lever.
- 125 130 11. In a recoil mechanism for a type key, a type bar, an upwardly disposed vibratory lever, means operatively connecting the vibratory lever and type bar comprising a backward pull link, a key lever, a reversely breaking actuating coupling operatively connecting the key lever and vibratory lever comprising a thrust link, a draw link moving the type bar to printing point upon depression of the key lever, means reversely breaking said coupling after the printing impact of the type bar, a return spring supported by a bar in the rear of the machine, a fulcrum trip link connecting the rear end of said draw link and return spring returning the type bar to normal position while key lever is in depressed position, means restoring said mechanism to normal operative position upon release of the key lever.
- 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

said coupling to normal operative position upon the release of the key lever.

13. In a typewriting machine, a type bar, a vibratory lever, a pivot rod supporting said vibratory lever intermediately the ends of the latter, a supporting bar extending across the machine supporting said vibratory lever pivot rod, means operatively connecting the vibratory lever and type bar comprising a backward pull link, a key lever, a reversely breaking actuating coupling operatively connecting the key lever and vibratory lever comprising a forward draw link curved downwardly horizontally disposed at the side 10 of the key lever operatively connected inter-

mediately of its ends to the vibratory lever and a forward thrust link operatively connecting the draw link and key lever, means reversely breaking said coupling after printing impact of the type bar for return of the type bar to normal position while key lever is in depressed position, said supporting bar of the vibratory lever pivot rod communicating with the thrust link returning said coupling to normal operative position upon release of the key lever.

Signed at Fort Collins, in the county of Larimer and State of Colorado, this 19th day of March, A. D. 1927.

ORVILLE U. DESHA.
